[57] **CLAIM**

The ornamental design for a housing for a rolling mill, as shown and described.

DESCRIPTION

FIG. 1 is a side perspective view of a housing for a rolling mill showing our new design;

FIG. 2 is a right side view thereof;

FIG. 3 is a left side view thereof;

FIG. 4 is a rear view thereof;

FIG. 5 is a front view thereof;

FIG. 6 is a top plan view thereof;

FIG. 7 is a bottom plan view thereof;

FIG. 8 is a side view of the housing for a rolling mill shown in FIG. 1, with a motor arranged laterally thereon;

FIG. 9 is a side view of the other side thereof;

FIG. 10 is a side view of the housing for a rolling mill shown in FIG. 1, with a motor arranged on the top;

FIG. 11 is a side view of the housing for a rolling mill shown in FIG. 1, with two motors arranged laterally thereon; and,

FIG. 12 is a front view of the housing for a rolling mill shown in FIG. 1, with two motors arranged on the top.
